UNITED STATES PATENT OFFICE.

HAROLD R. McDERMOTT, OF WATERLOO, IOWA.

UNSTEPPED FREQUENCY AUDIOMETER.

Application filed April 27, 1928. Serial No. 104,951.

My invention relates to improvements in audiometers, and particularly to those which are electrically controlled.

One object of my invention is to supply a device of this class capable of being controlled to produce evenly variable audible tones in oscillations ranging per second from 20 up to and beyond the limits of audibility.

Another object is to render it possible by means of the controls of said device to produce and hold any plurality of such oscillations per second within the range of audibility, while controlling the volume or intensity of the tones down to the weakest possible intensity audible by any given person.

The above objects are attained by the employment of the means illustrated in the accompanying diagram, as hereinafter described and claimed.

Hitherto devices such as tuning forks in a series of differing pitch capacity have been used for testing hearing, but these are necessarily limited to tones which are widely separated by steps in pitch or intensity, leaving omitted tones therebetween which render them insufficient in the proper continuously variable testing of audibility as to complete range.

Audiometers, electrically controlled, have been supplied but also fail in perfection because the controlling means thereof operate by steps in functioning, whereby also there are gaps produced in the numbers of oscillations or pitch, which is unsatisfactory in practise.

My device is therefore arranged to avoid these inconveniences, by being controllable to cover the complete range of audible oscillations or pitch per second by variation either way evenly and without breaks or steps intermittently, so that a perfect control of audiofrequencies is attained in practice.

With the above objects in view, and it being understood that modifications may be made in the features of the illustrative diagram submitted herewith without departing from the invention, I have supplied a device including a plurality of circuits, A, B and C, which cooperate to effect the above desired results.

Referring to the accompanying diagram, the circuit A is an oscillator inductively coupled circuit with both inductance and capacity, so arranged as to generate a fixed frequency well above audibility and having at 10 its own B battery supply of electric cur-

rent for the plate 12 of the oscillator tube 9. The circuit B is similar to A, but has a variable capacity or condenser 11^a instead of the fixed condenser 11 of A, for generating variable frequencies, also above audibility, and having its own B battery supply at 10^a. Aside from the above it will be seen that both of the circuits A and B have the same components, such as the induction coils 6, 7, and 6^a and 7^a; the interposed induction coils 8 and 8^a; and the oscillator tubes 9 and 9^a, with their plates, grids and filaments 12, 13 and 14, and 12^a, 13^a and 14^a, respectively. The circuit B contains in its grid line 35 the resistance 33 and 70 condenser 34 as a grid leak.

The circuit C is an ordinary detector one, containing the detector 18 with its plate, grid and filament 19, 20 and 21; its A battery at 22 with conductor 15 connected to the filaments 14 and 14^a; and a voltmeter 23 connected across the filament at 15^a to the part 15' of the conductor 15. In the C circuit, a conductor 16 leads from the detector grid 20 to the respective induction coils 8 and 8^a of the circuits A and B, including a condenser 27 and a resistance 26. A conductor 17 is in circuit between the battery 10^a and the conductor 31 leading to the ear-phones 32, including a condenser 30 and a resistance 29, 85 the latter for adjusting the volume of tone produced in the receiver 32.

The circuits A and B, being both regenerative, are when closely associated, preferably inclosed in separate copper compartments 1 and 2 respectively, which shield them from each other as to interference, the conductors which issue from each being further protected by like partitions as at 3, 4, 5, 36 and 37.

When the circuits A and B are oscillating at the same frequency, there are no oscillations picked up by the induction coils 8 and 8^a and consequently no differential impulse detected by the circuit C. However, when the circuit B is tuned at a higher or lower 100 frequency than the circuit A, the induction coils pick up the beat caused by this difference, whereby the frequency of the oscillation is equal to the difference in frequencies of circuit A and circuit B. This oscillation being picked up by the detector C and passing through the ear-phones 32, produces a tone equal to that of the frequency of the oscillation. This tone, if it happens to be within the range of audio frequency, is therefore 110 audible.

It will be seen that any tone whatever

within the range of audiofrequency is evenly attainable by this device, according to the variable control thereof above described, so that there are no gaps between oscillations in this range, affording therefore perfect testing of hearing by disclosing a lack of acuity in a perceptive organ of the internal ear.

Having described my invention, what I claim as new, and desire to secure by Letters Patent, is:

An audiometer comprising a detector circuit inductively coupled with two circuits of higher than audio frequency, the latter circuits respectively including fixed and variable condensers, whereby variations caused to be produced in the variable condenser originate non-stepped heterodynes in the detector circuit. 15

In testimony whereof I affix my signature.
HAROLD R. McDERMOTT.
